UNITED STATES PATENT OFFICE.

EDWARD A. ROCKWELL, OF NEW YORK, N. Y., ASSIGNOR TO E. A. ROCKWELL COMPANY, INC., OF NEW YORK, N. Y., A CORPORATION OF NEW YORK.

SYSTEM FOR FEEDING BY MEANS OF A VACUUM.

1,360,027.

Specification of Letters Patent. Patented Nov. 23, 1920.

Application filed June 4, 1919. Serial No. 301,827.

To all whom it may concern:

Be it known that I, EDWARD A. ROCKWELL, a citizen of the United States, residing at New York city, in the county of New York and State of New York, have invented a certain new and useful Improvement in Systems for Feeding by Means of a Vacuum, of which the following is a specification.

My invention relates particularly to an apparatus designed for feeding liquids of various kinds, but has special reference to apparatus designed for feeding liquid fuel to automobile engines or to analogous engines or devices.

Another object of my invention is to provide a feeding system of this character which is so constructed that a large volume of fuel may be fed. Again the object of my invention is to provide an apparatus in which there is a vacuum tank or chamber adapted to be supplied with fuel by means of the vacuum of the internal combustion engine with which it is connected, said vacuum tank being arranged to discharge very rapidly into an auxiliary supply tank or chamber through an opening normally closed by a valve which may be readily unseated by means of a relatively small force exerted thereon. Another object of my invention is to provide a simple construction of this character which may be manufactured at a minimum cost. Still another object of my invention is to provide an apparatus in which the degree of vacuum applied is maintained substantially constant irrespective of different engine speeds and different degrees of vacuum applied by the engine at different times, so as to obtain thus a uniformity in operation of the apparatus, and increase the volume of fuel which may be carried by the vacuum tank owing to the small size of the operating float contained therein. The object of my invention is, furthermore, to in this way provide a feeding system which has sufficient capacity and speed of operation to supply engines of large horse power, as for example engines used for driving heavy motor vehicles.

Further objects of my invention will appear from the detailed description thereof contained hereinafter.

While my invention is capable of embodiment in many different forms, for the purpose of illustration I shall show only one

form of my invention in the accompanying drawings, in which;

Figure 1 is a vertical section of an apparatus made in accordance with my invention.

Fig. 2 is a plan view partly in section of the vacuum chamber of an auxiliary supply tank.

Fig. 3 is a vertical section showing the cover for the vent pipe, and

Figs. 4, 5 and 6 are diagrammatic views showing the different positions of the parts in the operation of the apparatus.

In the drawings, I have shown a vacuum tank or chamber 1, which may be connected by means of a pipe 2 to a main-supply tank 70 for fuel, such as gasolene, and which may be connected also by a pipe 3, having a small port 3^a, to the intake manifold of an internal combustion engine, such for example as an automobile engine. The discharge end 75 of the pipe 2 may be screw threaded in a sleeve 3^b which may have a groove 3^c to receive a ring 3^d which may hold in place a screen 3^e, so as to prevent the entry of dirt into the apparatus. At the top of 80 the chamber 1, there is, furthermore, provided an automatic means for vacuum release, preferably comprising valve casing 3^f, which carries therein a vacuum release valve 3^g shown as pressed upwardly against its 85 seat by a spring 3^h supported by a cross pin 3ⁱ. A cover 3^j prevents the entry of dirt into the valve casing 3^f. The lower free edge of the chamber 1 may have a shouldered flange 4 which fits over the top or 90 separating plate of an auxiliary supply tank or chamber 5, and may be secured thereto by means of screws 6. Said auxiliary supply tank 5 may have a bottom closure 7 which may be connected by a pipe 8 to the carbureter of the internal combustion engine above referred to. A vent pipe 9 may extend upwardly from the top of the tank 5 through the chamber 1, and out through the top of the latter through a socket 10. 95 The exterior of the socket 10 may be screw-threaded to receive a hexagonal cover 11 which maintains a packing 12 around the upper end of the vent pipe 9, and which may have a circular cap 13 secured to the top of the cover 11, so as to allow spaces 14 at intervals around the cap 13 through 100 which air may pass. In the interior of the

105

tank or chamber 1 there may be a bracket 15 which may be secured to the vent pipe 9 for guiding a rod 16 which projects upwardly from a small upper float 17, made of any desired material, but preferably balsa wood. Below the float 17 there is shown rigidly connected a still smaller float 18 also made of any desired material, but preferably of balsa wood, the purpose of which is merely, 10 by a buoying action, to balance the weight of the upper float, said lower float being nearly always submerged. In this way, although until the level of the liquid reaches the float 17 there will be no tendency for the 15 float 17 to be elevated, nevertheless when said float 17 is reached by the level of the liquid it will be given a sudden strong lifting effort so as to move the parts attached thereto positively and quickly. The rod 16 20 may be extended below the buoying float 18 where it may be pivoted to a lever 19. This lever 19 may have at its other end a link 20 which may connect it to an arm 21 attached to one side of a valve closure 22 adapted to 25 fit against the underside of a valve seat 23 carried in an opening in the top of the tank 5. In the preferred form of float-operated valve adapted for use in the present organization, lever 19 may have at one side a projection 24 to contact with a projection 25^a on the link 20, so as to prevent lateral displacement of the valve 22 when it is being seated. In the initial opening movement of 30 the valve 22 the lever 19 rotates in this construction shown upon a pivot 25^a by means of which the lever 19 is connected by a lever 25^b to a pivot 25^c on the top of the tank 5. Afterward, however, the opening movement of the valve 22 is completed 35 by the rotation of the lever around the pivot 25^c. The valve 22 in closing is moved by the lever 19 on the pivot 25^a as a fulcrum. At the top of the lever 25^b there may be a stop 25^d which limits the movement thereof relative to the lever 19, and at the bottom of the lever 25^b there may be a stop 25^e between which and the top of the tank 5 there is normally a slight clearance to permit the valve 22 to be closed tightly. 40 by the vacuum applied to the top thereof, but this clearance is removed at the beginning of the opening movement of the valve 22 when the liquid begins to rise in the tank 5. The chamber 1 and the tank 5 may be 45 supported by means of a bracket 26^a surrounding the lower portion of the tank 5, which bracket may have an upwardly-directed tongue 27 adapted to be secured by screws 28 to the dash board or any other part of an automobile. Welded or otherwise secured to the top of the tongue 27 there may be a metal strap 29 having at one 50 end thereof a hook 30 for engagement with a yoke 31 connected by a square ring 32 to 55 a loop 33 on the other end of the strap 29,

In the operation of my invention, a supply of fuel, such as gasoline, having been introduced into the main supply tank which may be at a lower level than the auxiliary supply tank 5, as for example at the lower 70 rear portion of an automobile, and the engine having been started so as to intermittently form a vacuum in the vacuum chamber 1 through the port 3^a, the fuel will be drawn from the main supply tank by means 75 of the pipe 2, and discharged into the vacuum chamber 1, as shown in Fig. 4, which indicates the position of the parts when the valve 22 is closed. Inasmuch as the valve 22 is retained closed by the vacuum which is in the vacuum chamber 1, as well as the weight of the float 17, the liquid fuel will accumulate in the chamber 1 until the liquid level rises above the float 18, and finally reaches the float 17 whereupon a sudden lifting effort of considerable strength will be applied to the rod 16 which will first cause the stop 25^e to contact with the top of the tank 5, and then depress the side of the valve 22 to which the arm 21 is attached. 80 This will unseat the valve 22, as shown in Fig. 5, although the valve 22 is of such large area that the buoyancy of a float in the chamber 1 would not be sufficient to open the valve 22 against the force of the 85 vacuum holding the same closed if the link 20 were connected to the center of the valve. In this way, a powerful leverage acts by means of the lever 19 to initially open the valve 22. Once that the valve 22 is unseated in this manner, the vacuum will be broken and the lever 19 will then change its center of rotation from the pivot 25^a to the pivot 25^c, so as to entirely open the valve 22, and permit the quick discharge of a large volume of liquid from the chamber 1 into the tank 5. The opening of the valve 22 is completed by the force of gravity moving the valve into position, shown in Fig. 6. In this way, a constant supply of fuel will be 95 provided in the auxiliary tank 5, and the fuel will flow therefrom into the carburetor, whence the mixed air and gasoline will be supplied to the internal combustion engine. In the closing movement of the valve 22, it will be understood that the lever 19 will rotate upon the pivot 25^c until the valve 22 is closed, the valve being closed 100 very quickly because of the long leverage with which it is operated. Whenever the 105 valve 22 is closed, there will be a vacuum again developed in the tank 1, but this vacuum will be of a comparatively uniform character because of the fact that at every suction stroke of the engine piston, the vacuum release valve 3^b will open to an extent proportionate to the degree of vacuum applied by the engine. The presence of this valve 3^b, therefore, also decreases the vacuum 110 which is applied to the upper side of the 115 valve 22. It will be understood that the lever 19 will rotate upon the pivot 25^c until the valve 22 is closed, the valve being closed 120 very quickly because of the long leverage with which it is operated. Whenever the 125 valve 22 is closed, there will be a vacuum again developed in the tank 1, but this vacuum will be of a comparatively uniform character because of the fact that at every suction stroke of the engine piston, the vacuum release valve 3^b will open to an extent proportionate to the degree of vacuum applied by the engine. The presence of this valve 3^b, therefore, also decreases the vacuum 130 which is applied to the upper side of the

valve 22, and consequently renders it possible to open said valve with a very much smaller lifting effort of the float than would otherwise be the case. For this reason, the 5 float 17 and as a consequence the float 18 are both made smaller than would otherwise be possible, and smaller than would unseat the valve 22 if the valve 3* were absent. The capacity of the tank 5 is, therefore, 10 correspondingly greater, and this as well as the valve construction which permits a rapid feed of the fuel permits the use of my feeding system in connection with high powered engines. By constructing the apparatus in this manner, furthermore, the vacuum feed will be just as effective when there is a very low vacuum produced by the engine as when there is a normal vacuum or a high vacuum produced. The uniform 15 operation of the valve 22 is, furthermore, insured by the presence of the screen 3* which prevents the entry of particles of dirt into the apparatus. The tank 5 is at all times vented to the outer air through the 20 vent pipe 9. Whenever it is desired to repair the apparatus in any manner, it can readily be removed by disengaging the yoke 31 from the hook 30, bending the ends of the strap 29 apart, and disconnecting the 25 pipes 2, 3 and 8 from the chamber 1 and the tank 5.

While I have described my invention above in detail, I wish it to be understood that many changes may be made therein 30 without departing from the spirit thereof.

I claim:

1. In combination a vacuum chamber, an auxiliary supply tank, a valve providing communication between the same, means for 40 operating the valve comprising a float, and another float for balancing the weight of the first mentioned float.

2. In combination a vacuum chamber, an auxiliary supply tank, a valve providing 45 communication between the same, means for operating the valve comprising a float, and another float for balancing the weight of the first mentioned float, said first mentioned float being located a considerable distance 50 above the other float.

3. In combination a vacuum chamber, an auxiliary supply tank, a valve providing communication between the same, means for 55 operating the valve comprising a float, a lever connecting the float to the valve, and linkage for shifting the pivot of the lever to provide increased leverage at the beginning of the opening movement of the valve.

4. In combination a vacuum chamber, an auxiliary supply tank, a valve providing 60 communication between the same, means for operating the valve comprising a float, a lever connecting the float to the valve, and linkage for shifting the pivot of the lever to provide increased leverage at the beginning 65 of the opening movement of the valve.

of the opening movement of the valve, comprising a lever pivotally supporting said first mentioned lever.

5. In combination a vacuum chamber, an auxiliary supply tank, a valve providing 70 communication between the same, means for operating the valve comprising a float, a lever connecting the float to the valve, linkage for shifting the pivot of the lever to provide increased leverage at the beginning 75 of the opening movement of the valve, comprising a lever pivotally supporting said first mentioned lever, and stops on the second mentioned lever to limit the movement of the first mentioned lever. 80

6. In combination a vacuum chamber, an auxiliary supply tank, a valve providing communication between the same, means for 85 operating the valve comprising a float, a lever and link connecting the float to the valve, and linkage for shifting the pivot of the lever to provide increased leverage at the beginning of the opening movement of the valve.

7. In combination a vacuum chamber, an auxiliary supply tank, a valve providing 90 communication between the same, means for operating the valve comprising a float, a lever and link connecting the float to the valve, and linkage for shifting the pivot of 95 the lever to provide increased leverage at the beginning of the opening movement of the valve, comprising a lever pivotally supporting said first mentioned lever.

8. In combination a vacuum chamber, an auxiliary supply tank, a valve providing 100 communication between the same, means for operating the valve comprising a float, a lever and link connecting the float to the valve, linkage for shifting the pivot of the 105 lever to provide increased leverage at the beginning of the opening movement of the valve, comprising a lever pivotally supporting said first mentioned lever, and stops on the second mentioned lever to limit the 110 movement of the first mentioned lever.

9. In combination a vacuum chamber, an auxiliary supply tank, a valve providing 115 communication between the same, means for operating the valve comprising a float, a lever and link connecting the float to the valve, and linkage for shifting the pivot of the lever to provide increased leverage at the beginning of the opening movement of the valve, said link being connected to the valve 120 at one side thereof.

10. In combination a vacuum chamber, an auxiliary supply tank, a valve providing 125 communication between the same, means for operating the valve comprising a float, a lever and link connecting the float to the valve, and linkage for shifting the pivot of the lever to provide increased leverage at the beginning of the opening movement of the valve, comprising a lever pivotally sup- 130

porting said first mentioned lever, said link being connected to the valve at one side thereof.

11. In combination a vacuum chamber, an auxiliary supply tank, a valve providing communication between the same, means for operating the valve comprising a float, a lever and link connecting the float to the valve, linkage for shifting the pivot of the lever to provide increased leverage at the beginning of the opening movement of the valve, comprising a lever pivotally supporting said first mentioned lever, and stops on the second mentioned lever to limit the movement of the first mentioned lever, said link being connected to the valve at one side thereof.

12. In combination a vacuum chamber connecting with a main supply tank, an auxiliary supply tank, a valve providing communication between the vacuum chamber and the auxiliary supply tank adapted to permit the passage of liquid and gaseous materials, and an automatic vacuum release valve for the vacuum chamber.

13. In combination a vacuum chamber connected with a main supply tank, an auxiliary supply tank, a valve providing communication between the vacuum chamber and the auxiliary supply tank adapted to permit the passage of liquid and gaseous materials, and an automatic spring-pressed vacuum release valve for the vacuum chamber.

14. In combination a vacuum chamber connected with a main supply tank, an auxiliary supply tank, a valve providing communication between the vacuum chamber and the auxiliary supply tank adapted to permit the passage of liquid and gaseous materials, means for operating the valve comprising a float, and an automatic vacuum release valve for the vacuum chamber.

15. In combination a vacuum chamber connected with a main supply tank, an auxiliary supply tank, a valve providing communication between the vacuum chamber and the auxiliary supply tank adapted to permit the passage of liquid and gaseous materials, means for operating the valve comprising a float, and an automatic spring-pressed vacuum release valve for the vacuum chamber.

16. In combination a vacuum chamber, an auxiliary supply tank, a valve providing communication between the same adapted to permit the passage of liquid and gaseous materials, means for operating the valve

comprising a float, and a vacuum release valve for the vacuum chamber, said float being smaller than sufficient to unseat said valve in the absence of the vacuum release valve.

17. In combination a vacuum chamber, an auxiliary supply tank, a valve providing communication between the same adapted to permit the passage of liquid and gaseous materials, means for operating the valve comprising a float, and a spring-pressed vacuum release valve for the vacuum chamber, said float being smaller than sufficient to unseat said valve in the absence of the vacuum release valve.

18. In combination a vacuum chamber connected with a main supply tank, an auxiliary supply tank, a valve providing communication between the vacuum chamber and the auxiliary supply tank, means for operating the valve, and an automatic vacuum release valve for the vacuum chamber.

19. In combination a vacuum chamber connected with a main supply tank, an auxiliary supply tank, a valve providing communication between the vacuum chamber and the auxiliary supply tank, means for operating the valve comprising a float, and an automatic vacuum release valve for the vacuum chamber.

20. In combination, a vacuum chamber, an auxiliary supply tank, a valve providing communication between the same, means, comprising a float, for operating said valve, and an additional float, adapted to buoy said valve-operating float, to facilitate the opening and consequent flow of liquid through said valve.

21. In combination, a vacuum chamber connected with a main supply tank, an auxiliary supply tank, a valve providing communication between the vacuum chamber and the auxiliary supply tank, means for operating the valve, and an automatic vacuum release for the vacuum chamber.

22. In combination, a vacuum chamber connected with a main supply tank, an auxiliary supply tank, a valve providing communication between the vacuum chamber and the auxiliary supply tank, means for operating the valve comprising a float, and an automatic vacuum release for said vacuum chamber.

In testimony that I claim the foregoing, I have hereunto set my hand this 12th day of May, 1919.

EDWARD A. ROCKWELL.
